UNITED STATES PATENT OFFICE.

CHARLES M. WOODMAN, OF CHICAGO, ILLINOIS.

GUN-CLEANER.

SPECIFICATION forming part of Letters Patent No. 681,163, dated August 20, 1901.

Application filed April 2, 1900. Serial No. 11,140. (No model.)

To all whom it may concern:

Be it known that I, CHARLES M. WOODMAN, a citizen of the United States, and a resident of Chicago, in the county of Cook and State of Illinois, have invented certain new and useful Improvements in Gun-Cleaners, of which the following is a full, clear, and exact description, reference being had to the accompanying drawings and letters of reference marked thereon.

The object of my invention is to provide a simple, cheap, and effective reciprocating device for cleaning gun-barrels and other tubular objects which will rotate while being thrust into the bore, but will not rotate while being withdrawn, in which the plug used in connection therewith will not require clamping devices to hold it in operative position, and in which the rod when made in sections for convenience in carrying it about or to adapt it for tubular bodies of greater or less depth will not become separated in the bore thereof when in operation. This I accomplish by the means hereinafter fully described and as particularly pointed out in the claims.

In the drawings, Figure 1 is a side view of my invention, showing the rod broken in parts and a portion thereof in section. Figs. 2 and 3 are perspective views of counterpart clutch-disks. Fig. 4 is a side view of the parts of the plug of said cleaner. Fig. 5 is a longitudinal section of my invention, showing the rod broken away where it would pass through the clutches in the plug and with the cleaning-brush omitted.

In the drawings, A represents a screw-threaded rod generally of a length exceeding the depth of the bore of a gun-barrel and preferably comprising several sections 1 2 3, each of which is provided with screw-threaded dowels a on one end and a correspondingly threaded socket at the other to join them to their mates. Attached to the end section of this rod inserted in the gun-barrel is a brush B, and loosely journaled on the reduced cylindrical end portion of the opposite or outer end section is a handle C.

The rod A is given a rotary motion when thrust into the bore of the tubular body which it is desired to clean by means of a plug, through which it passes. This plug consists of a slightly-tapering shell b, of suitable sheet

metal, the ends of which are closed by cores c, of wood or other material, which are provided with central openings, through which the rod can freely pass. The lengths of said cores are such that a chamber e is left between them, in which an independent disk-shaped clutch E is placed and plays back and forth. The side of the clutch E facing the inner end of the rod A is provided with one or more radially-arranged serrations f of ordinary pitch, and it is provided with a bore g, having a female screw corresponding to that of the rod A. When said rod A is pushed inward, these serrations are adapted to engage correspondingly-shaped radially-arranged notches h in the non-revolvable counterpart F, which latter consists of a flat disk fitting within the bore of the shell b, that is secured to the inner core d of the plug and has a central opening concentric therewith.

In operation the tapered plug is pushed into the mouth of the gun-barrel until friction thereof against the sides of the bore holds it fast. The rod is thereupon thrust into said barrel and at the outstart carries said clutch into engagement with its counterpart, which being prevented thereby from rotating causes the rod to rotate, while further inward pressure is applied to the loose handle and until the desired limit of the inward movement of said rod is reached. When the rod A is withdrawn or moved outward by pulling on the loose handle, the initial effect is to disengage the clutch E from its counterpart and bring its smooth face against the smooth end of the outer core c of the plug, against which it will revolve, while the rod unaffected thereby will without revolving move outward. The cleansing action of the brush, which thus revolves only while advancing into the gun-barrel, is greater than if it revolved when moving in both directions; but aside from this advantage by the removal of the pressure on the plug, which it would be necessary to exert if the rod was revolved during the withdrawal movement thereof, the plug is enabled to retain its position in the mouth of the gun-barrel without the aid of extraneous clamping devices, which it would not otherwise be able to do. By making said rod A in sections it can be lengthened or shortened to fit any barrel. The threads on the dowels of

each section are such that the revolutions of the rod during the inward movement thereof is against the same. As said rod does not revolve when moved outward, the joints of the said sections thereof will not unscrew.

What I claim as new is—

1. A cleaner for tubular bodies comprising a screw-threaded cleaner-rod, a bushing adapted to frictionally engage the mouth of the bore of a tubular body, an apertured disk secured in either end of said bushing encircling said rod, an apertured disk having screw-threaded engagement with said rod and sliding and rotative engagement with said bushing between said end disks and means within the bushing locking said interior disk against rotation only when said rod is moved toward said tubular body.
2. A cleaner for tubular bodies comprising a screw-threaded cleaner-rod, a bushing adapted to frictionally engage the mouth of the bore of a tubular body, an apertured disk encircling said rod secured in the outer end of said bushing, an apertured disk encircling said rod, secured in the inner end of said bushing, an apertured disk having screw-threaded engagement with said rod and rotative, sliding engagement in said bushing and means on said interior disk and inner end disk to lock said interior disk against rotation when said rod is moved toward said tubular body.
3. A cleaner for tubular bodies comprising

a screw-threaded cleaner-rod, a bushing adapted to frictionally engage the mouth of the bore of said tubular bodies, an apertured disk encircling said rod secured in the outer end of said bushing, an apertured disk having screw-threaded engagement with said rod and sliding, and rotary engagement with said bushing and a lug on the face of said interior disk adapted to engage a lug on said inner end disk and lock said interior disk from rotating, when said rod is moved toward said tubular body.

4. A cleaner for tubular bodies comprising a screw-threaded cleaning-rod, an exteriorly tapered bushing adapted to frictionally engage the mouth of the bore of a tubular body, an apertured disk encircling said rod secured in the outer end of said bushing, an apertured disk encircling said rod secured in the inner end of said bushing, an apertured disk having screw-threaded engagement with said rod and sliding, and rotary engagement with said bushing, and a lug on the face of said interior disk adapted to engage a lug on said inner end disk and lock said interior disk from rotating, when said rod is moved toward said tubular body.

CHARLES M. WOODMAN.
